FINGERPRINTING DEVICE

James E. Harris, Smyrna, Tenn.

Application August 10, 1950, Serial No. 178,740

3 Claims. (Cl. 41—4)

1

This invention relates to finger printing devices and has more particular reference to a device for holding and moving a finger print card during the various steps of recording finger prints thereon.

One object of the present invention is to provide a novel and improved finger printing machine including means for holding a finger print card in proper position to have finger prints impressed thereon and feeding means for feeding the card through the machine so that successive horizontal rows of finger prints may be impressed on the card.

Another object of the present invention is to provide a finger printing machine, as characterized above, wherein all the operations may take place without the operator touching the card between the time it is placed in the machine and removed therefrom.

Another object of the present invention is to provide a finger printing machine, as characterized above, in which the card for receiving the finger imprints may be easily and quickly placed in the machine, and during its passage through the machine is held out of the way of the operator and the person being finger printed so as not to interfere with the taking of the impressions.

A further object of the invention is to provide a finger printing machine which is simple and inexpensive in construction and efficient in operation.

Other objects and advantages of the invention will appear in the following specification when considered in connection with the accompanying drawings, wherein:

Fig. 1 is a plan view of a preferred form of a finger printing machine constructed in accordance with the present invention;

Fig. 2 is a front elevational view of the machine shown in Fig. 1;

Fig. 3 is a left hand side elevational view of the machine shown in Fig. 1;

Fig. 4 is a vertical sectional view taken on the line 4—4 of Fig. 2; and

Fig. 5 is a fragmentary horizontal sectional view taken on the line 5—5 of Fig. 2.

Referring now to the drawings, there is shown a preferred form of a finger printing machine, constructed in accordance with the present invention and comprising a base or support 10; a housing 11 mounted on the base and having a flat top which forms a platen for supporting a finger print card; a shaft 12 mounted in the housing and carrying a plurality of spaced feed

2

rollers 13 thereon; a second or upper housing 14 pivotally mounted on and above the housing 11 and carrying a shaft 15 having spaced idle rollers 16 mounted thereon in position to engage and cooperate with the feed rollers 13 to advance a finger print card through the machine; a pair of spring assemblies, indicated generally at 17, for normally holding the housing 14 in a position to cause the idle rollers 16 to grippingly engage the feed rollers 13; a gate 18 positioned in front of the housing 11 for holding the lower portion of a card inside the housing; an idle roller 19 mounted in the gate 18; and an idle roller 20 mounted in the housing 11 in position to cooperate with the idle roller 19 to facilitate the movement of the finger print card through the machine.

The base or support 10 is shown as comprising a generally rectangular block 21, preferably made of wood and having a felt base 22 suitably secured thereto, as by means of adhesive.

The housing 11 comprises a generally rectangular, hollow, open bottom and open front box-like structure, preferably made of sheet metal and having end walls 23, 24, a rear wall 25, and a top wall 26, which forms a platen for supporting a finger print card.

The bottom edges of the end walls 23, 24 are secured to rectangular strip metal plates 27, 28, respectively, which, in turn, are suitably secured to the base member 10, as by screws.

The top wall 21 extends forwardly beyond the base member 10 and has its forward edge curved downwardly and rearwardly to form an overhanging ledge 29 (see Figs. 3 and 4).

The shaft 12 extends longitudinally through the housing 11 with its ends extending through and journaled in the end walls 23, 24. The projecting ends of the shaft 12 have knurled knobs 30, suitably secured thereon, as by set screws. The feed rollers 13, four such being shown, are secured in longitudinal spaced relation on the shaft 12, as by set screws. Preferably, the rollers 12 are made of metal and have their outer peripheries knurled. The upper portions of the rollers 13 project through elongated slots 31 formed in the top wall 16 of the housing 11 (see Figs. 4 and 5).

The open front of the housing 11 is partially closed by a gate 18 composed of a flat strip of sheet metal 32 having rectangular blocks 33, 34 secured on its inner face at each end. The gate is swingably mounted on the housing, as by means of a vertical hinge pin 35 extending through the block 34 and having its upper end

journalled in the overhang of the top wall of the housing and its lower end journalled in a block 36 secured to the base member 10.

Suitable latch means are provided for holding the gate in its closed position and, as shown, such means comprises an elongated, resilient metal strip 37 secured to the end wall 23 of the housing and having a spring clip end 38 adapted to snap over the end of the gate and hold it shut against the front of the housing, as shown in Fig. 3.

As shown in Figs. 2 and 4, the height of the gate and its mounted position are such that sufficient clearance is left between the top of the gate and the bottom of the overhang of the top wall of the housing and the bottom of the gate and the top of the base member 21, to provide ample clearance for the passage of a finger print card therethrough, in a manner to be hereinafter described.

The idle roller 19 is mounted in the gate 18 and extends longitudinally thereof with its ends journalled in the blocks 33, 34.

The idle roller 20 is mounted within the front lower portion of the housing 11 and extends longitudinally thereof with its ends journalled in the side walls of the housing. Each of the rollers 19 and 20 preferably, and as shown, comprises an elongated wooden cylinder 39 secured on a metal shaft 40.

The upper housing 14 comprises a generally rectangular, hollow, open bottom and open back, box-like structure, having a top wall 41, end walls 42, 43, and a front wall 44. The housing 14 is pivotally mounted on and between the upper ends of a pair of vertical brackets 45, each of which is secured to an end wall of the housing 11. The brackets 45 support the upper housing in a raised position above the top of the lower housing 11 and with the front wall of the upper housing spaced rearwardly from the forward edge of the top wall of the lower housing 11 (see Fig. 3).

The shaft 15 extends longitudinally through the housing 14 with its ends journalled in the end walls thereof. The idle rollers 16, four such being shown, are suitably secured in longitudinally spaced relation on the shaft 15 in position for each idle roller to engage a corresponding feed roller 13 on the shaft 12 (see Fig. 5).

Spring assemblies, indicated generally at 17, are provided for normally holding the idle rollers 16 in gripping engagement with the feed rollers 13 so that the finger print card held between the idle rollers and the feed rollers will be advanced through the machine as the shaft 12 is rotated by the knurled knobs on the ends thereof, and, as shown, such assemblies may comprise a spaced pair of posts 46 having their upper ends reduced, as shown at 47, and having their lower ends secured to the rear ends of the metal strips 27 and 28; compression springs 48 mounted on the posts and engaging washers, which, in turn, engage the under sides of the extensions 49 formed on the side walls 42, 43 of the housing 14. The extensions 49 have elongated slots 50 formed therein which receive the reduced upper ends 47 of the posts 46. The upward pressure of the springs turns the housing 14 about its pivotal axis so that the idle rollers 16 are held in tight engagement with the feed rollers 13.

A spaced pair of L-shaped spring clip members 51 have their upstanding rear ends secured to the front wall 44 of the upper housing 14 and have their laterally extending arms 52 normally

resting upon the front end portion of the top wall of the lower housing (see Figs. 1 and 4). The spring clip arms 52 may be raised from the surface of the top plate of the upper housing by swinging the front end portion of the upper housing upwardly about its pivotal axis.

A spaced pair of guide members 53 are suitably secured, as by welding, on the top wall of the housing 11 along the side edges and adjacent to the front end thereof (see Figs. 1 and 2). Each of the guide members 53 is shown as comprising an elongated strip of metal having one of its longitudinal edges bent under and upwardly against the rest of the strip.

While the machine of the present invention may be used with any usual type of finger print card, it is especially designed for use with finger print cards of the type used by the Federal Bureau of Investigation. The manner in which the machine operates is shown in Figs. 3 and 4. The operator inserts a finger print card, indicated at C, under the spring clips 52 and the guides 53, and pushes it toward the rear of the machine until the top edge of the card is in position to be engaged by the idle rollers 16 and the feed rollers 13, when a slight turn of the knobs 30 will engage the card between the rollers (see Fig. 3). The idle rollers and the feed rollers will grip the end of the card and the spring clip members 52 will hold the card securely on the platen formed by the top wall of the housing 11, in position to receive the first longitudinal row of imprints of the fingers of the person being finger printed, as shown in Fig. 1. Then, the operator opens the gate 18, bends the portion of the finger print card extending over the front of the machine downwardly behind the gate, then he closes the gate so that the card will be held in the machine in the position shown in Fig. 4. After the first horizontal row of finger imprints have been made, the card is fed into the machine by the operator turning the knurled knobs on the shaft carrying the feed roller, to bring the card into position to receive the second horizontal row of finger imprints. This procedure is followed until the card has been completed and it is pulled out of the rear of the machine by the operator.

It should be noted that the idle rollers 16 and 20 guide the lower portion of the card as it passes through the front portion of the housing 11 and that at all times the lower portion of the card is held out of the way with no danger of its inadvertently getting smeared with ink or otherwise damaged. It should also be noted that the idle rollers 16 are very narrow so as to prevent their rolling over the imprints after they have been taken. The narrow idle rollers 16 only engage the card along a line between the imprints. Also, the spring clip members 52 are so positioned as to engage the card along lines between the spaces for receiving the finger imprints, as shown in Fig. 1.

From the foregoing, it readily will be seen that there has been provided a novel and improved finger printing machine which will hold a finger print card and permits movement therethrough without the operator touching the card between the time it is placed in the machine and removed therefrom; one which is simple and inexpensive in construction, easy to operate, and efficient in use.

Obviously, the invention is not restricted to the particular embodiment thereof herein shown and described.

What is claimed is:

1. In a finger printing machine, a platen having a rounded front end; spaced parallel guides positioned along the forward side edges of said platen for holding and guiding a finger print card during its travel over the platen; means for feeding the finger print card over the platen comprising manually operated feed rollers; and guide means positioned below and rearwardly of the front end of said platen for engaging and holding the portion of the finger print card not on the platen in a position under the platen and out of the way of the operator and the person being finger printed, said guide means comprising a fixed guide member extending transversely of the platen and a swingable guide member pivotally connected below and at one side of the platen, the construction and arrangement being such that the swingable guide member may be moved to an open position to permit the projecting portion of a finger print card mounted on the platen to be bent downwardly around the rounded front edge of the platen and rearwardly into engagement with the fixed guide member and moved to a closed position to hold the finger print card against the fixed guide member.

2. In a finger printing machine, a platen having a rounded front end; spaced parallel guides positioned along the forward side edges of said platen for holding and guiding a finger print card during its travel over the platen; means for feeding the finger print card over the platen comprising manually operated feed rollers; and guide means positioned below and rearwardly of the front end of said platen for engaging and holding the portion of the finger print card not on the platen in a position under the platen and out of the way of the operator and the person being finger printed, said guide means comprising a fixedly mounted guide roller extending transversely of said platen; a gate member pivotally mounted below and at one side of the platen; and a guide roller mounted in the gate member in position to cooperate with said fixedly mounted guide roller when said gate is in closed position, the construction and arrangement being such that the gate may be swung to an open position to permit the lower portion of a finger print card mounted on the platen to be bent downwardly against the fixedly mounted roller and then swung to its closed position in which the lower portion of the finger print card will be held between and guided by the guide rollers.

3. A finger print machine comprising a gener-

ally rectangular base member; a platen having a rounded front end and a transverse row of spaced aligned slots positioned rearwardly of said front edge; supporting members mounted on said base member with their upper ends secured to the side edges of said platen for supporting it in position above said base member; a shaft journaled in said supporting member and extending transversely of and below said platen; a plurality of feed rollers secured in spaced relation on said shaft, each roller positioned so that a portion of its periphery extends through one of said slots; a housing pivotally mounted upon said supporting member in a position above said platen; a shaft mounted in said housing and carrying a plurality of idle rollers, each positioned above one of said feed rollers; spring means normally urging said housing about its pivotal axis to hold said idle rollers in gripping engagement with said feed rollers; spaced parallel guides mounted on the forward side edges of said platen for guiding a finger print card during its travel over the platen; a spaced pair of spring clamp members carried by said housing and positioned to extend forwardly over the forward end of said platen to hold down a finger print card thereon, said rollers and said spring clamp members being spaced so as to correspond with the spaces between the imprints made on the finger print card so as to avoid smearing the imprints; an idle roller journaled in said side supports and extending below and transversely of said platen; a swingable gage member pivotally mounted on said base member at one side of the front end of said platen, an idle roller carried by said gage member and positioned to cooperate with said last named idle roller when said gage member is in closed position, the construction and arrangement being such that the gage may be swung to an open position to permit the lower portion of a finger print card mounted on the platen to be bent downwardly against the fixedly mounted roller and then swung to its closed position in which the lower portion of the finger print card will be held between and guided by the guide rollers.

JAMES E. HARRIS.
